UNITED STATES PATENT OFFICE.

JAMES PATERSON, OF ELIZABETH, NEW JERSEY, ASSIGNOR TO PAGE, WILDER & CO., OF HALLOWELL, MAINE.

DESIGN FOR AN OIL-CLOTH PATTERN.

Specification forming part of Design No. 5,393, dated November 28, 1871.

To all whom it may concern:

Be it known that I, JAMES PATERSON, of the city of Elizabeth, county of Union and State of New Jersey, have invented or produced a new and original Design for Oil-Cloth or other Fabrics; and I do declare that the following is a full and exact description of the same.

A general ground, 1, of drab color, a diamond figure, 2, of white on the drab, encompassed by a narrow white line, 3, about the eighth of an inch wide, said white line connected at the corners 4, surrounded with light-brown bands 5 with loops 6, said loops lapping over the four corners of the white diamond figure 2, said brown bands crossing on the drab ground on the opposite or outside, 7, forming a diamond figure filled

up with a figure, 8, composed of mechanical shapes of green, yellow, red, and chocolate colors. A light figure of a cross, 9, occupies the center of the white diamond, with a small red diamond figure, 10, in the middle. The rest of said light figure is made up of yellow and drab colors, and may be considered the center of the design.

What I claim is—

The general conformation of the design herein shown with the present or other colorings of the same.

JAMES PATERSON.
